CLAIM

The ornamental design for a folding razor, as shown and described.

DESCRIPTION

FIG. 1 is a perspective view of a folding razor showing my new design in operative position;

FIG. 2 is a rear elevational view thereof;

FIG. 3 is a front elevational view thereof;

FIG. 4 is a left side elevational view thereof;

FIG. 5 is a top plan view thereof;

FIG. 6 is a top plan view of the razor in unfolded position; and

FIG. 7 is a side elevational view of the razor folded into a box configuration.
